Primary Examiner — Michelle E. Wilson*Assistant Examiner* — Clese Moore, Jr.(74) *Attorney, Agent, or Firm* — Sand, Seboll & Wernow Co., LPA(57) **CLAIM**

The ornamental design for a bike support plank, as shown and described.

DESCRIPTION

FIG. 1 is a front, left, top, isometric perspective view of a bike support plank in accordance with my design;
 FIG. 2 is a front, right, top, isometric perspective view thereof of the bike support plank shown in FIG. 1;
 FIG. 3 is a top plan view thereof;
 FIG. 4 is a bottom plan view thereof;
 FIG. 5 is a front elevation view thereof;
 FIG. 6 is a rear elevation view thereof;
 FIG. 7 is an enlarged right end elevation view of the bike support plank shown in FIG. 2; and,
 FIG. 8 is an enlarged left end elevation view thereof.
